Primary Examiner — T Chase Nelson*Assistant Examiner* — Jonathan J. Han*(74) Attorney, Agent, or Firm* — The Dobrusin Law Firm, P.C.; Bryan S. Lemanski(57) **CLAIM**

The ornamental design for a dash mount, as shown and described.

DESCRIPTION

FIG. 1 is a perspective view of a dash mount showing my new design.

FIG. 2 is a top plan view of FIG. 1.

FIG. 3 is a left side elevational view of FIG. 1.

FIG. 4 is a front elevational view of FIG. 1.

FIG. 5 is a right side elevational view of FIG. 1.

FIG. 6 is a back elevational view of FIG. 1; and,

FIG. 7 is a bottom plan view of FIG. 1.

The broken lines in the drawings show portions of the dash mount that form no part of the claimed design.

1 Claim, 4 Drawing Sheets
